(57) **CLAIM**

The ornamental design for an electrical fitting for non-metallic electrical cable, as shown and described.

DESCRIPTION

FIG. 1 is a top, front and right side perspective view of an electrical fitting for non-metallic electrical cable showing my new design;

FIG. 2 is a top plan view thereof;

FIG. 3 is a right side elevation view thereof, the left side elevation view being a mirror image thereof;

FIG. 4 is a bottom plan view thereof;

FIG. 5 is a rear elevation view thereof;

FIG. 6 is a front elevation view thereof; and,

FIG. 7 is a right side elevation view thereof.

The broken line in the figure drawing views is included for the purpose of illustrating unclaimed environment and forms no part of the claimed design.

1 Claim, 4 Drawing Sheets
